DESIGN FOR A COUCH OR SIMILAR ARTICLE

Lydia Tschernjakow and Terence H. Robsjohn-Gibbings, New York, N. Y.

Application August 19, 1942, Serial No. 107,970

Term of patent 3½ years

To all whom it may concern:

Be it known that we, Lydia Tschernjakow and Terence H. Robsjohn-Gibbings, respectively a citizen of no country and a subject of the King of Great Britain, and residents of the city of New York, county and State of New York, have invented a new, original, and ornamental Design for a Couch or Similar Article, of which the following is a specification, reference being had to the accompanying drawing, forming part thereof.

Fig. 1 is a perspective view of the base unit of the couch or similar article; and

Fig. 2 is a perspective view of the couch or similar article, showing our new design.

We claim:

The ornamental design for a couch or similar article, substantially as shown.

LYDIA TSCHERNJAKOW.
